FILLING END REMOVER

Carl D. Brown, Hopedale, Edward C. Nichols, Upton, and George F. Belforti, Milford, Mass., assignors to Draper Corporation, Hopedale, Mass., a corporation of Maine

Application April 26, 1940, Serial No. 331,844

15 Claims. (Cl. 139—256)

The present invention pertains to automatic looms and more particularly relates to the control and removal of filling ends formed by such looms.

Automatic looms commonly have a reciprocating lay with a shuttle box at the replenishing end thereof, and filling replenishing mechanism for automatically replenishing the filling supply whenever the latter becomes substantially exhausted. Operation of the replenishing mechanism incidentally results in the formation of an incoming filling end which projects from the cloth selvage, and commonly also results in a similarly projecting outgoing filling end. The loom includes parting means such as a temple thread cutter for parting the filling end adjacent the cloth selvage, and another parting means for parting and clamping the outgoing filling ends adjacent the shuttle box. As constructed commercially, such looms have not commonly included any means whatever for collecting the parted filling ends and removing them from the loom, such ends being left hanging from the magazine of the replenishing mechanism or from the said clamping means.

25 The filling ends when left hanging as just described are apt to be caught in moving parts of the loom, particularly the lay, shuttle box or picker, and drawn into the cloth, thus forming a defect in the cloth. The problem of collecting and removing the pieces of filling ends to prevent these defects in the cloth has been vexatious and long standing.

Numerous attempts to solve the aforesaid problem have been made heretofore. For example, it has been proposed to remove the filling ends by a suction pipe located adjacent the shuttle box and connected to a vacuum pump. Other proposals include swinging hooks or arms, operated at the time of filling replenishment, to engage the filling ends and carry them to some point not so close to the lay and shuttle box. However, these prior constructions have been unsatisfactory because they are expensive, complex and unreliable, and they have not been used commercially to any appreciable extent.

It is accordingly a principal object of the present invention to provide an automatic loom having a lay, shuttle box, replenishing mechanism, and parting means as aforesaid and a filling end remover comprising a conduit leading from a point adjacent the shuttle box to a point remote therefrom and mechanical means for engaging the filling ends and feeding them into and through the conduit, the conduit being provided

with means for removing the filling ends from the mechanical feeding means, additional means for preventing retrograde movement of the filling ends in the conduit, and means for preventing contact between the conduit and the mechanical feeder, whereby such ends shall be automatically prevented from being woven into the cloth.

The foregoing and other objects of the invention are accomplished in the construction illustrated on the accompanying drawings, of which:

Fig. 1 is a perspective view of the replenishing side of an automatic loom having the preferred embodiment of our invention applied thereto;

Fig. 2 is a plan view of certain mechanism shown on Fig. 1;

Fig. 3 is a detail view, partly in section, to a larger scale, showing part of the filling end remover of Figs. 1 and 2, and

Fig. 4 is a view in elevation taken from the left of Fig. 3.

The loom shown on the drawings is but fragmentarily illustrated, the parts and mechanism not shown being of usual construction which is well known in the art and forms no part of the present invention. In addition, certain of the parts that are shown are old and well known, they being of the present invention only in that they are illustrative of parts that may be used in the combination defined in the appended claims. The old parts include a loom frame, of which, part of a right hand loom side 1 and a breast beam 2 are shown, and also include a reciprocating lay of which the lay beam 3, reed 4, and shuttle box 5 are shown. The shuttle box 5 is located at the replenishing end of the lay, which in the present instance is at the right hand side of the loom.

A shuttle 6 carrying the filling supply is picked from side to side of the loom, along the lay beam 3, by suitable means which may include a picker 40 stick 7. As the shuttle is thus picked, it lays filling thread in the shed S which filling thread is beaten into the fell of the cloth C by the reed 4. When the filling supply in the shuttle is substantially exhausted, a fresh supply is provided 45 by suitable automatic replenishing mechanism. The replenishing mechanism may be of any suitable usual construction, such as the bobbin changing mechanism indicated at 8. This mechanism includes a magazine 9 holding 50 reserve bobbins 10 which are transferred to the shuttle as needed. The ends f of the filling on the bobbins 10 are attached to a fixed holder 11 on the magazine.

The transfer of a bobbin 10 to the shuttle 6

55

and the subsequent picking of the shuttle results in the formation of a length of filling thread which extends from the holder 11 through the shed S. The subsequent beating in of the portion 5 of this thread which is in the shed leaves the end f projecting from the cloth selvage. This filling end is known in the art as the incoming filling end. When the loom is operating with a filling 10 feeler, not shown, the replenishing operation results in formation of another filling end f' projecting from the cloth selvage. This end f' extends from the selvage to the outgoing bobbin the 15 shuttle and is known as the outgoing filling end. These filling ends are thus formed by the operation of the replenishing mechanism, but the formation is incidental to the major function, replenishing the filling supply.

The outgoing filling end f' must be parted, at 20 the time of transfer, between the cloth selvage and the shuttle. This parting may be effected by any usual means, that shown including parting and clamping blades 12. These blades are normally closed, to grip a filling end f' as shown, but are moved rearwardly toward the shuttle 25 box and are simultaneously opened, just prior to each replenishing operation. The opening of the blades 12 releases the filling end f' held thereby. Then, as the replenishing operation takes place, the blades are again closed to part 30 and clamp the new outgoing filling end and the blades are again moved forwardly. This parting and clamping mechanism is not of the present invention, it being disclosed and claimed in 35 patent to Stafford, No. 1,552,388 granted Sept. 1, 1925, to which patent reference may be had for a more complete disclosure.

The filling ends f and f' are parted adjacent the cloth selvage by any suitable means, such as the usual temple thread cutter 13. Both such 40 filling ends may be supported between the thread cutter 13 and the thread cutter 12 by a hook 14 which is fixed on the loom frame. This hook is not new, per se, but may be found desirable for reasons that will become apparent. The incoming filling end f may be further supported by a fixed wire 15 which extends over the shuttle box 45 adjacent the outer end thereof.

It will be apparent that, even when hook 14 and support 15 are used, the cutting of the filling 50 ends by cutter 13 leaves the ends substantially free and uncontrolled. The free ends are very apt to float or be blown onto moving parts of the loom, and more particularly onto the lay and shuttle box, from whence they may be carried 55 into the shed S by the shuttle 6, thus causing a defect in the cloth. The defects thus caused, on prior looms, are fairly numerous, and are of serious consequence particularly in the better 60 grades of fabrics including rayon and the like. It is to prevent these defects that we have provided the filling end removing means hereinafter described for automatically conveying the filling ends away from the moving parts of the loom.

65 In accordance with the present invention, the said removing means comprise a conduit leading away from the moving parts of the loom, and mechanical means for feeding the filling ends into and along said conduit. The particular 70 conduit 16 shown on the drawings is tubular in form and open at both ends. This conduit 16, is fixed in a bracket 17, which may be supported by the stud 18 on which the cutting and clamping mechanism which includes the blades 12 are 75 usually mounted. As thus supported, the con-

duit is located beneath magazine 9 and directly in front of the shuttle box 5 intermediate the ends of the latter.

The filling ends f and f' withdraw from the shuttle box 5 as the lay moves rearwardly following a replenishing operation. Thereafter, the filling ends project from the cloth selvage longitudinally of the lay, in front of the shuttle box. The rearward end 19 of the conduit 16 is located directly in front of these filling ends, which point 10 is adjacent the shuttle box when the lay is in its forward position. The conduit extends forwardly from its rearward end, to any suitable point that is sufficiently remote from the moving parts of the loom, particularly the lay and shuttle box. 15 The forward end 20 of the particular conduit 16 is located over the top of the usual ejected-bobbin receptacle 21.

It will be apparent that various suitable 20 mechanical means may be devised for feeding the filling ends into and through a conduit such as the conduit 16. However, the preferred form shown is simple and very effective. This preferred form comprises a member 22 in the form 25 of a plunger. The member 22 has a single, continuous reciprocating motion which may be imparted by the lay. To this end, the member 22 may be attached to the lay by being pivotally connected at its rearward end to a bracket 23 on the front of the lay 3. The member 22 extends 30 forwardly from the bracket 23 into the conduit 16 and is preferably of sufficient length that it is not completely withdrawn from the conduit even when the lay is in its rearward position.

The construction so far described, except for 35 the pivotal connection, may be similar to that disclosed and claimed in the co-pending application of Carl D. Brown, Serial No. 284,028 filed July 12, 1939, now Patent No. 2,206,832.

When the member 22 is located as just described, the filling ends f and f' will sag into engagement with the member as soon as they are cut by the temple thread cutter 13. The member 22 has projections 24 which thereupon engage the filling ends and push them forwardly 45 into the rear end of conduit 16. The projections 24 extend circumferentially of the member 22 and are radially inclined, each projection having a radial front face and a forwardly inclined rear face as shown more clearly by Fig. 3. When thus formed, the projections are adapted to feed the filling ends in one direction only, i. e., forwardly. The forward end of the member 22 has attached thereto a guide 25, shown in detail in Figs. 3 and 4. The guide has side walls corresponding in 55 shape to the walls of the conduit 16 but of lesser diameter to permit the guide to freely slide within the conduit. The top of guide 25 is convex and flush with the top of member 22. The bottom 26 of guide 25 is concave for a purpose later 60 to be described.

The total movement of the member 22 is appreciably less than the total distance the newly 65 formed filling ends must travel from their first point of engagement with the member 22 until they emerge from the front end of the conduit 16. The member 22 accordingly must reciprocate several times, feeding the filling ends forwardly with an intermittent motion, to feed the filling ends entirely through the conduit. In other 70 words, the member 22 feeds the ends forwardly a short distance, then moves rearwardly leaving the ends stationary, and then feeds the ends forwardly, etc. The particular construction shown is effective to produce the desired intermittent 75

feeding action, only if the conduit is provided with means for preventing retrograde or rearward movement of the filling ends. To accomplish this purpose the rearward end of conduit 16 may be provided with suitable means to catch or hook the filling ends and remove them from the member 22 and hold them against retrograde movement on the rearward movement of member 22. The particular catch or hook shown comprises a pair of oppositely disposed openings 27 located adjacent the rear end of member 16, a pair of inwardly projecting cut outs 28 located at the rear end of conduit 16 and a pair of forwardly inclined slots 29 leading from the cut outs 28 to the openings 27, the intersection of the bottom walls of the slots with the openings forming hooks 30. The inwardly projecting cut outs 28 together with the slots 29 form guides leading to the hooks 30. As the member 22 moves forwardly into the conduit 16 carrying the filling ends, the filling ends will enter the inwardly projecting cut outs 28, ride up the inclined slots 29 and fall into the openings 27 behind the hooks 30.

Additional means are provided in conduit 16 for preventing retrograde movement of the filling ends, the particular structure shown comprises a longitudinal row of integral inwardly projecting tongues 31 struck up from the bottom of the conduit 16. Each of these tongues is triangular in shape and has a radial front face and a forwardly inclined rear face as shown more clearly in Fig. 3.

The operation of the device is as follows.

The filling ends *f* and *f'* sag into engagement with the member 22 as soon as they are cut by the temple thread cutter 13. The projections 24 on the forward movement of member 22 will engage the filling ends and carry them forward into the rearward end of the conduit 16. As the member 22 moves forwardly into the conduit 16, carrying the filling ends, the filling ends will enter the inwardly projecting cut outs 28, ride up the inclined slots 29 and fall into the openings 27 where they will again engage with member 22. On the rearward movement of member 22 the hooks 30 will prevent retrograde movement of the filling ends. On its rearward movement the member 22 moves rearwardly to an extent where its forward end and the guide 25 are rearward of the openings 27 and hooks 30 thereby permitting the filling ends to drop to the bottom of openings 27 and thereby be placed in a position to be engaged by the guide 25 on the subsequent forward movement of member 22 in conduit 16. On such subsequent forward movement of member 22 in conduit 16, the guide 25 contacts the filling ends and pushes the portions of the filling ends engaged by the guide 25 through conduit 16 to the end thereof. When the filling ends in their entireties have been pushed through the conduit 16 they drop into the ejected-bobbin receptacle 21. The longitudinal row of tongues 31 will on the rearward movement of member 22 catch and prevent retrograde movement of the filling ends that are not pushed completely through conduit 16. The concave bottom 26 of guide 25 straddles the row of tongues 31 and prevents contact between the member 22 and the conduit 16, the side walls of guide 25 are of lesser diameter than the diameter of conduit 16 to provide space for the filling ends between the two members. The pivotal connection of the member 22 to the lay cooperates with the guide 25 to prevent contact of the member 22 with the conduit 16.

We find that with the construction above de-

scribed, the outgoing filling end *f'* is very rapidly fed entirely through the conduit 16 and dropped into the receptacle 21. The incoming filling ends *f* are likewise fed through the conduit as far as permitted by their connection to the holder 11. When a number of incoming filling ends accumulate in the conduit, they may be broken by a single movement of the operator's hand and then will promptly feed through the conduit and fall into the receptacle 21. In the meantime, these ends are effectively held entirely out of any position where they might be caught and carried into the cloth.

Having fully disclosed the preferred embodiment of our invention, we claim:

1. In a filling end remover for automatic looms, the combination of a conduit leading away from the moving parts of the loom, a reciprocating member constructed and arranged to engage the filling ends and feed them into and along said conduit from one end thereof to the other, means pivotally connected to said member for giving motion thereto and means for guiding said member in its movement within said conduit.

2. In a filling end remover for automatic looms, the combination of a conduit leading away from the moving parts of the loom, a reciprocating member constructed and arranged to engage the filling ends and feed them into and along said conduit, said conduit having holding means for preventing retrograde movement of said filling ends, said holding means comprising rigid inwardly projecting members.

3. In a filling end remover for automatic looms, the combination of a reciprocating member 35 having means intermediate its ends for engaging the filling ends and removing them from the moving parts of the loom, hook means positioned adjacent the path of reciprocation of said reciprocating member for removing said filling 40 ends from said reciprocating member and holding them in position in front of said reciprocating member, said reciprocating member being constructed and arranged to engage said filling ends when so positioned and push them further from 45 the loom and means spaced from said second named means for preventing retrograde movement of said filling ends upon retraction of said reciprocating member.

4. In a filling end remover for automatic looms, 50 the combination of a reciprocating member having means intermediate its ends for engaging the filling ends and removing them from the moving parts of the loom, a fixed member relative to which said reciprocating member moves, means 55 adjacent one end of said fixed member for removing said filling ends from said reciprocating member and holding them in position in front of said reciprocating member, said reciprocating member being constructed and arranged to engage said filling ends when so positioned and push them further from the loom, and means located on said fixed member at a point spaced from said second named means for preventing retrograde movement of said filling ends upon 60 retraction of said reciprocating member.

5. In a filling end remover for automatic looms, the combination of a reciprocating member having means intermediate its ends for engaging the filling ends and removing them from 70 the moving parts of the loom, a fixed member relative to which said reciprocating member moves, said fixed member having means adjacent one end for removing said filling ends from said reciprocating member and holding them in 75

- position in front of said reciprocating member, said reciprocating member being constructed and arranged to engage said filling ends when so positioned and push them further from the loom, 5 means spaced from said second named means for preventing retrograde movement of said filling ends upon retraction of said reciprocating member, and means for guiding said reciprocating member in its movement in relation to said fixed member.
6. In a filling end remover for automatic looms, the combination of a reciprocating member having means intermediate its ends for engaging the filling ends and removing them from the moving parts of the loom, a fixed conduit within which said reciprocating member moves, said conduit having hook means adjacent one end thereof for removing said filling ends from said reciprocating member and holding them in position in front of said reciprocating member, whereby said filling ends may be pushed further from the loom, means carried by said conduit and spaced from said second named means for preventing retrograde movement of said filling ends upon retraction of said reciprocating member, and means carried by said reciprocating member for guiding it in its movement within said conduit.
7. An automatic loom having filling replenishing mechanism, a reciprocating lay having a shuttle box at the replenishing end thereof, and a filling end remover, said remover comprising a reciprocating member pivotally connected to said lay, said reciprocating member having means intermediate its ends for engaging the filling ends and removing them from the moving parts of the loom, a fixed member relative to which said reciprocating member moves, hook means adjacent one end of said fixed member for removing said filling ends from said reciprocating member and holding them in position in front of said reciprocating member, said reciprocating member being constructed and arranged to engage said filling ends when so positioned and push them further from the loom, means spaced from said hook means for preventing retrograde movement of said filling ends upon retraction of said reciprocating member, and means for guiding said reciprocating member in its movements in relation to said fixed member.
8. An automatic loom having filling replenishing mechanism, a reciprocating lay having a shuttle box at the replenishing end thereof, and a filling end remover, said remover comprising a member pivotally connected to said lay and reciprocated thereby, said member having means intermediate its ends for engaging the filling ends and removing them from the moving parts of the loom, a fixed conduit within which said member reciprocates, said conduit having hook means adjacent one end thereof for removing said filling ends from said reciprocating member and holding them in position in front of said reciprocating member, whereby said filling ends are pushed further from the loom and along said conduit, means carried by said conduit for preventing retrograde movement of said filling ends upon retraction of said reciprocating member and means for guiding said reciprocating member in its movements within said conduit.
9. An automatic loom having filling replenishing mechanism, a reciprocating lay having a shuttle box at the replenishing end thereof, and a filling end remover, said remover comprising a reciprocating member pivotally connected to said lay for reciprocation thereby and extending for- 10 wardly from said lay, said reciprocating member having guiding means at its forward end and having means intermediate its ends for engaging the filling ends and removing them from the moving parts of the loom, a fixed conduit 15 extending forwardly from a point in front of said shuttle box within which the forward portion of said reciprocating member moves, said conduit having hook means adjacent its rear end and guide means for guiding said filling ends 10 into said hook means and also having a longitudinal row of inwardly projecting members extending substantially throughout its length, said guiding means on said reciprocating member having a concave bottom surface and side walls corresponding in shape to the side walls of said conduit whereby upon movement of said reciprocating member contact with said row of inwardly projecting members in said conduit will be prevented and filling ends in said conduit will 20 be held between said side walls of said guiding means and said conduit and thereby moved forwardly on the forward motion of said reciprocating member.
10. An automatic loom having filling replenishing mechanism, a reciprocating lay having a shuttle box at the replenishing end thereof, and a filling end remover, said remover comprising a fixed conduit extending forwardly from a point in front of said shuttle box and having hook 30 means adjacent its rear end and a longitudinal row of inwardly projecting tongues extending substantially throughout its length, a filling end feeding member pivotally connected to said lay for reciprocation thereby and having a guide on 35 its forward end and means intermediate its ends for engaging the filling ends and feeding them into said conduit, said feeding member moving on its forward stroke to the forward end of said conduit and moving on its rearward stroke to a point rearwardly of said hook means, said guide preventing contact between said feeding member and said row of inwardly projecting tongues throughout the movement of said feeding member.
11. In a filling end remover for automatic looms, the combination of a conduit leading away from the moving parts of the loom, a reciprocating member constructed and arranged to engage the filling ends and feed them into and along 50 said conduit and means for reciprocating said member, said conduit having a pair of oppositely disposed openings adjacent its rear end, a pair of cut-outs extending inwardly from the rear end of said conduit toward said openings and upwardly inclined slots connecting said cut-outs with said openings, the intersection of the bottom edges of said slots with said openings providing hooks for removing said filling from said feeding member upon rearward movement of 60 said member, and a longitudinal row of integral inwardly projecting tongues struck up from the bottom of said conduit for preventing retrograde movement of said filling ends.
12. In a filling end remover for automatic 65 looms, the combination of a conduit leading away from the moving parts of the loom, a reciprocating member constructed and arranged to engage the filling ends and feed them into and along said conduit and means for reciprocating said member, 70 said conduit having a pair of oppositely disposed openings adjacent its rear end, a pair of cut-outs extending inwardly from the rear end of said conduit toward said openings and upwardly inclined slots connecting said cut-outs with said 75

openings, the intersections of the bottom edges of said slots with said openings providing hooks for removing said filling ends from said feeding member upon rearward movement of said member, and a longitudinal row of integral inwardly projecting tongues struck up from the bottom of said conduit, each of said tongues having a vertical front face and a rearwardly inclined rear face whereby retrograde movement of said filling ends is prevented.

13. An automatic loom having filling replenishing mechanism, a reciprocating lay having a shuttle box at the replenishing end thereof, and a filling end remover, said remover comprising a fixed conduit extending forwardly from a point in front of said shuttle box, and a filling end feeding member pivotally connected to said lay and extending forwardly within said conduit, said member having a guide at its forward end and for the greater portion of its length provided with a multiplicity of longitudinally spaced circumferential ridges, each of said ridges having a radial front face and a forwardly inclined rear face whereby said ridges engage and feed the filling ends forwardly, said conduit having at least one longitudinal row of integral inwardly projecting tongues each tongue having a radial front face and a rearwardly inclined rear face whereby upon the rearward movement of said feeding member the filling ends are retained within said conduit, said guide on said feeding member acting with said pivotal connection for preventing engagement between said ridges on said feeding member and said projections in said conduit.

14. In a filling end remover for automatic looms, the combination of a conduit leading away from the moving parts of the loom, a reciprocating member constructed and arranged to engage the filling ends and feed them into and along said conduit, said conduit having hook means adjacent its rear end for removing said filling ends from said reciprocating member upon rearward movement of said member, and said conduit also having a longitudinal row of integral inwardly projecting tongues, each of said tongues having a vertical front face and a rearwardly inclined rear face whereby retrograde movement of said filling ends is prevented.

15. In a filling end remover for automatic looms, the combination of a conduit leading away from the moving parts of the loom, a reciprocating member constructed and arranged to engage the filling ends and feed them into and along said conduit and means pivotally connected to said member for reciprocating same, said conduit having hook means adjacent its rear end for removing said filling ends from said reciprocating member upon rearward movement of said reciprocating member and guide means for guiding said filling ends into said hook means, and said conduit also having holding means for preventing retrograde movement of said filling ends.
